U. PRATT.
FRAME FOR BLEACHING IVORY, &c.

Patented Jan. 6, 1852.

No. 8,639.

UNITED STATES PATENT OFFICE.

ULYSSES PRATT, OF DEEP RIVER, CONNECTICUT.

PROCESS OF BLEACHING IVORY.

Specification of Letters Patent No. 8,639, dated January 6, 1852; Antedated July 6, 1851.

To all whom it may concern:

Be it known that I, ULYSSES PRATT, of Deep River, in the county of Middlesex and State of Connecticut, have invented a certain new and useful Improvement in Bleaching Ivory; and I do hereby declare that the following is a full, clear, and exact description of the same, reference being had to the accompanying drawings, forming part of this specification, in which—

Figure 1, is a perspective view of one of the frames. Fig. 2, is a longitudinal section of the same, represented as hanging under a sky-light. Fig. 3, exhibits a modification.

Similar letters of reference indicate corresponding parts in the several figures.

The modes or methods of bleaching thin pieces of ivory, for veneering piano keys and other purposes, by placing the ivory upon trays, boards and other flat supports without pins or stops to raise them from the surface, and covering the same with glass in frames placed at various angles, and sometimes suspending the ivory by strings and loops or otherwise, in front of a common glass window, are objectionable, not only on account of the slowness of the operation of bleaching but also on account of the imperfect character of the bleaching. Now in order to remove these evils and to expedite the operation of bleaching, and to render it more perfect, I have invented a new mode of presenting the ivory to the rays of the sun which accomplishes the desired objects and is described as follows.

A is a frame of wood or other suitable material of a suitable width to hang between the muntins or stiles of the sash of a skylight, and of any suitable length, divided lengthwise into two compartments, (but may be divided into any other number required) each compartment being bounded by a rib g; a row of studs a, a, a, of wood, metal, ivory, or other suitable material is provided on each side of each compartment of the frame to stand but a small distance above the surface of the frame and at convenient distances apart according to the width of the ivory; when the pieces to be bleached have parallel edges the studs on each side of a compartment should be opposite to each other.

B, B, represent strips of ivory to be bleached; they are first moistened or other-

wise prepared, and then placed on the frame with their lower edges bearing on the face of the frame and on the upper side of the studs a, a, a, their upper edges being supported on the ends or faces of the studs next above those on which their lower edges rest, each pair of studs supporting the lower edge of one strip and the upper edge of the strip below it, the strips thus rest only on four small points of their surface.

C, (Fig. 2) represents the frame of a sky-light which may be set at any desired inclination.

b is the glass.

c, is a small bar of wood or metal secured under the lower part of the frame.

d, is a button.

The frame A may be placed in the position shown at Fig. 2, its lower end supported by the bar c, and its upper end by the button d, or its upper end may be supported at different elevations by a cord e, in which there are several loops in one of which the screw f, at the top of the frame rests, the lower end being still supported by the bar c, (see red lines in Fig. 2).

By altering the elevation of the upper end of the frame A, it may be set at various inclinations according to the direction of the sun's rays; the strips of ivory may be supported on this frame in any position between a vertical and horizontal line without slipping out of place.

The modification shown in Fig. 3, consists in substituting a notched plate for the studs a, a, a.

I do not claim the bleaching of ivory upon a frame exposed to the rays of the sun passing through glass placed above the same, but

What I do claim as my invention and desire to secure by Letters Patent is—

The improvement in the process of bleaching ivory as set forth in the specification; that is to say, the raising up of one edge of the piece of ivory above the plane of the frame which supports it, and sustaining it in its place, in the manner described.

In testimony whereof I have hereunto signed my name before two subscribing witnesses.

ULYSSES PRATT
